TELESCOPIC UMBRELLA

Alois Völker, Leichlingen, Germany, assignor to
Rosenkaimer & Cie., Leichlingen, Germany, a
firm

Application September 8, 1950, Serial No. 183,851

5 Claims. (Cl. 135—26)

1

My invention relates to telescopic umbrellas comprising telescopic stick-shaped parts and telescopic head bar members.

Object of the present invention is to provide a telescopic umbrella the main struts of which are supported by auxiliary struts, thus forming an umbrella-frame capable of being shortened and having the advantage of simple structure and reliable operation. The top part or crown of the umbrella is only connected to upper telescopic head bar members, and lower telescopic head bar members are only supported by a single main strut each extending to a main sliding socket, the auxiliary strut of said main strut leading to an upper fast stick part.

A further object of the invention is to provide a collapsible umbrella wherein coacting stick sections and coacting rib members are adapted to be simultaneously telescoped.

A still further object of the invention is to provide a collapsible umbrella comprising telescoping stick sections and telescoping rib members with brace struts, and wherein the rib members are centrally connected to a crown in spaced relation to the stick sections.

Another object of the invention is to secure the telescopic head bar members in their pulled-out position one against each other by means of a projection or bulge upon a hollow rail of the upper head bar member so that the top part or crown and, thus, the upper head bar members are clamped one against each other.

For opening the umbrella it is first necessary to pull out the head bar members only, in contrary to prior art umbrellas of this type which require a telescoping of both the stick parts and the head bar members at the same time. As a result of this structural feature it is obtained a light running telescoping operation. Moreover the umbrella according to this invention has the further advantage that it can be opened in any position, i. e. even if directed upwards. The smallest displacing movement of the main sliding socket effects a radial outward movement of the head bars, as the auxiliary struts are supported by the top of the stick. A preliminary shaking of the umbrella for the purpose of straddling the head bar members is avoided by this structure. The umbrella-frame comprises a few parts only so that the structure is simple and the operation positive. Any auxiliary devices for opening or closing the umbrella are not necessary.

By way of example, the structural features of the telescopic umbrella redesigned according to this invention are set forth in the following speci-

fication and will be better understood by practitioners from the accompanying drawings, in which:

Fig. 1 shows a side view of the umbrella in shortened position;

Fig. 2 shows a side view of the umbrella in pulled-out position before the umbrella is opened;

Fig. 3 shows diagrammatically an intermediate position of the umbrella during the opening operation;

Fig. 4 shows a diagrammatical sectional view of the opened umbrella;

Fig. 5 shows a sectional view of a clamping device of the head bar members;

Fig. 6 is a section on line VI—VI of Fig. 5.

Similar letters refer to similar parts throughout the several views.

The telescopic umbrella according to this invention shown by way of example in Figures 1 to 6, comprises:

An upper stick part 1 is adapted to be telescoped into a lower stick part 2 as well as lower head bar members 4 into upper head bar members 3. The upper head bar members 3 have the shape of hollow rails enabling the lower head bar members 4 having the shape of solid rails to slide therein. Main struts 5 connect a runner or socket 6 with the top of the upper or outer head bar members 4 by means of so-called hinge members 9. Auxiliary struts 7 are hinged to the main struts 5, their free ends being fastened to the upper stick part 1. The telescopic upper head bar members 3 are held together by a top part or crown 8 being nowhere else connected to any other part of the umbrella-frame. In the upper position the runner or socket 6 is supported by a spring 10 in known manner. A set spring 11 mounted in the upper stick part 1 secures the lower position of the runner or socket 6. The set spring 11 is rounded at its two edges and provided with a notch 12 in its middle part adapted to engage the runner or socket 6. The rounded parts of the set spring 11 are formed with sharp, straight-lined shoulders 13a, 13b at both sides, thus making possible to secure the stick parts 1, 2 either in pulled-out position shown in Fig. 4 or in telescoped position shown in Fig. 2. As shown in Fig. 2 the lower end of the stick part 2 is provided with a slot enabling the set spring 11 to project through the stick part 2 when the stick parts are telescoped one into another. As usual the lower part of the stick part 2 is equipped with a handle 14.

The upper head bar members 3 are provided

with a projection or bulge 15 so as to secure the telescopic head bar members 3, 4 in pulled-out position. Said projection or bulge 15 effects a clamping action when the hinge member 9 connected to the lower head bar members 4 slides over the projection or bulge 15, thus preventing both an undesirable moving of the upper head bar members 3 along the lower head bar members 4 as well as a rigid condition of the umbrella during the position shown in Fig. 2.

The operation of the telescopic umbrella according to the invention described with reference to Figures 1 to 6, is as follows:

By pulling out the top part or crown 8 the head bar members are pulled out so that the umbrella is brought from the telescoped position shown in Fig. 1 to the position according to Fig. 2. Then the runner or socket 6 is pressed upwards so that it attains its upper working position. As a result of this, the stick parts are pulled out at the same time until the umbrella is entirely opened occupying the position shown in Fig. 4. In that opened position the self-centering top part or crown 8 lies against the upper stick part 1. During the closing movement the runner or socket 6 is moved downwards at the same time pressing the set spring 11 with its rounded portions 13a, 13b into the upper stick part 1. As a result of this, the stopping of the stick parts at the lower edge 13b is released at the same time. A further displacing of the runner or socket 6 then effects the telescoping of the upper stick part 1 into the lower stick part 2 until both stick parts have attained the position shown in Fig. 2. In this manner described the umbrella according to the invention is opened or closed as an umbrella of usual type. The stick parts are shifted during the closing respectively the opening operation. For shortening the umbrella merely the head bar members are telescoped by a light blow after overcoming the clamping action of the projection or bulge 15.

The manner of using and applying the illustrative embodiment of my invention set forth above will be clear from the foregoing description. It is, of course, to be understood that my invention is not limited to the specific embodiment thereof here shown and described for purposes of illustration only.

What I claim is:

1. A folding umbrella comprising telescoping upper and lower stick sections, a runner slideable on said stick sections, inner and outer telescoping rib members, a crown independent of the upper stick section and to which the inner ends of the inner rib members are connected, struts extending between the runner and the inner ends of the outer rib members and auxiliary brace members extending between the upper end of the upper stick section and the struts.

2. An umbrella as in claim 1, wherein the upper

stick section telescopes into the lower stick section, a spring member carried by the lower end of the upper stick section, abutment shoulders at opposite ends of the spring member selectively engageable with opposite ends of the lower stick section for holding the stick section in telescoped or extended positions, and the lower stick section having a slot therein adjacent its lower end for the projection of the spring member when the stick sections are in telescoped position.

3. An umbrella as in claim 1, wherein the upper stick section telescopes into the lower stick section, a spring member carried by the lower end of the upper stick section, abutment shoulders at opposite ends of the spring member selectively engageable with opposite ends of the lower stick section for holding the stick sections in telescoped or extended positions, the lower stick section having a slot therein adjacent its lower end

20 for the projection of the spring member when the stick sections are in telescoped position, and said spring member having a notch therein adapted to receive the runner for holding the ribs and struts in folded position.

25 4. A folding umbrella comprising telescoping upper and lower stick sections, a runner slideable over the stick sections, a spring member at the lower end of the upper stick section, the lower end of the lower stick section having a side slot

30 therein, abutment shoulders on opposite ends of the spring member respectively engageable with the upper end of the lower stick section when the umbrella is extended and engageable with a wall of said slot when the stick sections 35 are telescoped and rib, strut and brace members associated with the runner and the upper end of the upper stick section.

5. A folding umbrella comprising telescoping upper and lower stick sections and a runner thereon, telescoping inner and outer rib members, the inner ends of the inner ones of said rib members being connected to a crown, one-piece struts extending between the runner and the inner ends of the outer ones of the rib members 45 and auxiliary one-piece struts extending between the upper free end of the upper stick section and first named struts intermediate the ends of the latter.

ALOIS VÖLKER.
